Attorney

UNITED STATES PATENT OFFICE.

CHARLES STOECKLIN, OF MONTBELIARD, FRANCE.

REVOLUTION COUNTER.

Application filed November 1, 1921. Serial No. 512,121.

To all whom it may concern:

Be it known that J. CHARLES STOECKLIN, citizen of the Republic of Switzerland, residing at Montbeliard, Doubs, France, have 5 invented certain new and useful Improvements in Revolution Counters, of which the following is a specification.

This invention relates to revolution counters, and more particularly to counters embodying a plurality of separate counting mechanisms adapted to be selectively connected with the shaft or other device or element, the number of revolutions of which is to be counted. 10
 15 The invention resides primarily in the provision of improved means, hereinafter fully described, whereby any selected counting mechanism may be thrown into operation to the exclusion of the remaining counting mechanism or mechanisms, or of certain of them if more than two such mechanisms are utilized; the coupling or connecting action being effected at will with equal facility whether the counter is running or is stationary, and without requiring stoppage, or interfering with the counting operation. 20
 25
 30

According to the invention, the sets of number wheels constituting the counting mechanisms are disposed within a case which is equipped with a suitable dial and in which there is journalled a main shaft adapted to be connected in some desired way with the rotating or revolving work member, so that the revolving movement of the latter will be transmitted to said shaft. A reducing gear train leads from this shaft to a transmission shaft, whence the drive branches to each set of counting wheels, so 35 that there is, in effect, a driving connection between the main shaft and each counting wheel set; such drive preferably embodying a relatively wide gear or pinion fixed to the transmission shaft, and a sliding gear associated with and individual to each counting wheel set and located adjacent the first wheel thereof, all of the sliding gears constantly meshing with the wide fixed gear to be rotated thereby. 40
 45
 50 A clutch is interposed between each sliding gear and the adjacent counting or number wheel; and a device is provided which is operable at will from the exterior of the case and which engages all of the sliding gears, the arrangement being such that, in

the event of two counting mechanisms only being employed, either of them may be coupled with the drive shaft and the other one simultaneously uncoupled, due to the movement of the sliding gears in opposite directions along their respective shafts. 55

An embodiment of the invention is illustrated in the accompanying drawing, in which:

Figure 1 is a plan view of a counter 65 equipped with two counting mechanisms, the dial plate being removed.

Figs. 2 and 3 are cross-sections taken at right angles to each other on lines II-II and III-III, Fig. 1, respectively. 70

Referring more particularly to the drawing, *a* indicates a case which contains the various parts comprised in the counter, and in the side wall of which the main shaft *b* is journalled. This shaft projects exteriorly 75 of the case at one end and is provided at such point with a sprocket wheel *c*, or other suitable device, for connecting it with the shaft or the like (not shown), the revolutions of which are to be counted. A pinion *d* is mounted on shaft *b* within the case, and is in driving engagement with a gear *e* comprised in a reducing gear train leading to a shaft *f*, to which latter the rotation of shaft *b* is thereby transmitted. 80
 85

Counting is effected, as stated above, by means of a plurality of separate mechanisms or devices, each comprising a set of numeral wheels having transfer devices of some appropriate character between them to produce the carry-overs. Each set is loosely mounted on its respective shaft; and it is the purpose of the invention to selectively connect one set at a time with the shaft *f* to be driven therefrom, the other set or sets 90 being left inactive. In the construction illustrated, two sets, the wheels of which are designated *k* and *k'*, are employed; but it will be understood that such number may be increased, if desired, as has already been 95 stated.

The first wheel of each set is preferably provided with a suitable clutch member which is engageable by a complementary clutch member *h* or *i*, slidably mounted on 105 the respective counting or numeral wheel shaft. Both clutch members *h* and *i* are provided with peripheral gear teeth which constantly mesh with a comparatively wide gear or pinion *g*, fixed to shaft *f* to rotate 110

therewith; and both are also engaged by a spring *p* which tends to keep them constantly coupled to the clutch members on the adjacent numeral wheels *h* and *h'*. 5 This tendency of the spring is counteracted, however, by means of a device which permits only one clutch to be closed at a time; such device being here shown as comprising a rotatable cam plate or disk *m* of sinuous 10 profile which is marginally engaged in a circumferential groove *l* formed in the hub of each of the sliding clutch members *h* and *i*. Cam *m* is fixed to the inner end of a short shaft which is journalled in a bearing 15 opening in the side wall of the case and projects outwardly beyond the same to enable it to be operated at will by means of a lever *o*, or other suitable device, which is fastened to it; the shape of the cam being 20 such that when turned it will shift both clutch members *h* and *i* simultaneously, one toward and the other from, the complementary clutch members, so that one clutch will be closed and the other opened. Where 25 more than two sets of counting wheels and, hence, more than two clutches are employed, the controlling cam will be shaped to effect the clutching movement of one sliding clutch member only, the other clutch members being unclutched. Operation of the 30 cam may be effected at any desired time, either when the machine is in motion or when it is stationary, as will be apparent.

I claim as my invention:

- 35 1. A revolution counter, comprising a drive shaft; a plurality of sets of counting wheels; a driven shaft; a driving connection between the drive and driven shafts; a driving connection between the driven shaft and each set of counting wheels and including a clutch to control the drive; and a selecting device for closing a single selected clutch at a time.
- 40 2. A revolution counter, comprising a drive shaft; a plurality of sets of counting wheels; a driven shaft; a driving connection between the drive and driven shafts; a clutch member fixed to the first wheel of each set; a sliding gear individual to each 45 set and having a clutch member complementary to the fixed clutch member of that set; spring means tending to normally shift the sliding gears to close all of the clutches; a gear on the driven shaft with which all of 50 the sliding gears constantly mesh; and a selecting device to enable the movement of solely one selected gear at a time to engage the complementary fixed clutch member.
- 55 3. A revolution counter, comprising a drive shaft; a plurality of sets of counting wheels; a driven shaft; a driving connection between the drive and driven shafts; a driving connection between the driven shaft and each set of counting wheels and including a 60 clutch to control the drive; and a selecting device for simultaneously closing one clutch and opening another.
4. A revolution counter, comprising a drive shaft; a plurality of sets of counting wheels; a driven shaft; a driving connection between the drive and driven shafts; a driving connection between the driven shaft and each set of counting wheels and including a clutch to control the drive; and a selecting device engaged with all of the clutches for simultaneously closing any one selected clutch and opening another.
5. A revolution counter, comprising a drive shaft; a plurality of sets of counting wheels; a driven shaft; a driving connection between the drive and driven shafts; a driving connection between the driven shaft and each set of counting wheels and including a clutch to control the drive; and a rotatable selecting device within the case engaged with all of the clutches but operable to close only one selected clutch at a time.
6. A revolution counter, comprising a drive shaft; a plurality of sets of counting wheels; a driven shaft; a driving connection between the drive shaft and the driven shaft; a clutch member fixed to the first wheel of each set; a movable clutch member cooperative with each fixed clutch member to engage the same; means operated by the driven shaft for rotating all of the movable clutch members; and a selecting device for moving two of the movable clutch members in opposite directions with relation to the corresponding fixed clutch members, to couple one and uncouple the other.
7. A revolution counter, comprising a drive shaft; a driven shaft; a driving connection between the two shafts; two coordinate sets of counting wheels; a driving connection between the driven shaft and each set of counting wheels, each driving connection including a clutch embodying a clutch member fixed to the first wheel of the set and a movable clutch member for cooperation therewith and having a grooved hub; and a rotatable cam engaged with the grooved hubs of both movable clutch members for simultaneously engaging one of them with and disengaging the other one from, the corresponding fixed clutch members.
8. A revolution counter, comprising a drive shaft; a plurality of sets of counting wheels, the first wheel of each set having a fixed clutch member associated with it; a driving gear individual to each set and provided with a clutch member cooperative with the adjacent fixed clutch member; gearing connecting the drive shaft with all of the sets of counting wheels and including a gear with which all of the clutch gears constantly mesh; and means operable to move a single selected clutch gear, to the exclusion of the remaining clutch gear or gears, rela-

tively to the corresponding fixed clutch member to couple the two together.

9. A revolution counter, comprising a drive shaft; a plurality of sets of counting wheels, the first wheel of each set having a fixed clutch member associated with it; a driving gear individual to each set and provided with a clutch member cooperative with the adjacent fixed clutch member; gearing connecting the drive shaft with all of the sets of counting wheels and including a gear with which all of the clutch gears constantly mesh; and a cam operable at will to move a single selected clutch gear, to the exclusion of the remaining clutch gear or gears, relatively to the corresponding fixed clutch member to couple the two together.

10. A revolution counter, comprising a drive shaft; a plurality of sets of counting wheels, the first wheel of each set having a fixed clutch member associated with it; a driving gear individual to each set and provided with a clutch member cooperative with the adjacent fixed clutch member; gearing connecting the drive shaft with all of

the sets of counting wheels and including a gear with which all of the clutch gears constantly mesh; and selecting means operable at will to move a single selected clutch gear into engagement with, and another clutch gear out of engagement with, the corresponding fixed clutch members.

11. A revolution counter, comprising a drive shaft; a plurality of sets of counting wheels, the first wheel of each set having a fixed clutch member associated with it; a driving gear individual to each set and provided with a clutch member cooperative with the adjacent fixed clutch member; gearing connecting the drive shaft with all of the sets of counting wheels and including a gear with which all of the clutch gears constantly mesh; and a cam engaged with two clutch gears for simultaneously engaging one of them with, and disengaging the other one from, the corresponding fixed clutch members.

In testimony whereof I affix my signature.

CHARLES STOECKLIN.
